Primary Examiner — Mitchell I. Siegel*(74) Attorney, Agent, or Firm* — Payam Moradian(57) **CLAIM**

I claim the ornamental design for a guitar case, as shown and described.

DESCRIPTION

FIG. 1 is a front perspective view of the guitar case, showing my new design;

FIG. 2 is a front view thereof;

FIG. 3 is a rear view thereof;

FIG. 4 is a left side view thereof;

FIG. 5 is a right side view thereof;

FIG. 6 is an end view thereof;

FIG. 7 is an opposite end view thereof;

FIG. 8 is another front view thereof;

FIG. 9 is a front perspective view of a second embodiment of the guitar case of FIG. 1;

FIG. 10 is a front view of FIG. 9;

FIG. 11 is a rear view of FIG. 9;

FIG. 12 is a left side view of FIG. 9;

FIG. 13 is a right side view of FIG. 9;

FIG. 14 is an end view of FIG. 9;

FIG. 15 is an opposite end view of FIG. 9; and,

FIG. 16 is another front view of FIG. 9.

The broken lines shown are included for the purpose of illustrating unclaimed subject matter and forms no part of the claimed design.

1 Claim, 12 Drawing Sheets(56)
